UNITED STATES PATENT OFFICE.

JOE L. ULLATHORNE, OF MEMPHIS, TENNESSEE.

SEED-PACKET HOLDER.

SPECIFICATION forming part of Letters Patent No. 726,380, dated April 28, 1903.

Application filed July 8, 1902. Serial No. 114,766. (No model.)

To all whom it may concern:

Be it known that I, JOE L. ULLATHORNE, a citizen of the United States, residing at Memphis, Shelby county, State of Tennessee, have 5 invented certain new and useful Improvements in Seed-Packet Holders, of which the following is a specification.

My invention relates to certain new and useful improvements in seed-packet holders, 10 and has especial reference to unit holders adapted to hold a small number of packets—say one or two dozen—to be associated with other and similar holders in a case to display and store packages of seed, so that they can 15 be easily inspected or withdrawn for inspection or sale.

In the drawings, Figure 1 is a perspective view of my seed-packet holder empty. Fig. 2 is a perspective view of a case having 20 three shelves, two of which are filled with seed-packet holders. Fig. 3 is a reduced-scale pattern of one of the boxes.

Referring now to the drawings, in which like numerals indicate the same or like parts in all 25 the views, my holder consists of a box 1, having a back 2, sides 3, a bottom 4, a strip 5 at or near the bottom across the front, (which is open,) and a strip 6 across the front about two-thirds of the way to the top. This strip 30 is so placed because the packets which the boxes are designed to hold are of paper and must necessarily be held intermediate their length if they are to be effectually supported and because as the seed-packet holder being 35 comes empty the bottoms of the packets being the heavier, because the seed have settled there, may slip to the rear and the tops fall forward out of the holder if the said top strip is too near or at the top of the holder. 40 In making these boxes I first cut out a pattern, such as is shown in Fig. 3, making the bottom 4 and back 2 of sufficient width to accommodate the width of packet desired and making the depth of the sides 3 and 3^a 45 just what is needed to accommodate the length of the packet and scoring the paper along the dotted lines. The sides 3 are first folded up at right angles to the base 4, and the back 2 is brought up against them and

the sides 3^a folded outside. The front strip 5 is then bent up, and the ends 7 are brought between the sides 3 and 3^a. The box is held together by a strip 6 across the front, which strip is bent into a U, with the ends 8 of the legs of the U flattened out, as shown dotted at 8^a, and passed through both pieces 3 and 3^a on opposite sides and are then bent back, as shown, to hold the said sides together. The packets of seed 9 are placed in the box from the top and when the seed are slightly 60 shaken down bulge outward at the bottom, filling the shape of box shown more or less completely and evenly. When placed in the case 10, each holder may be withdrawn and filled separately and then may be withdrawn 65 for examination or removal of seed-packets. After a box becomes nearly empty a wad of paper may be stuffed behind the packets to hold them forward, giving the display always the effect of a full case. 70

The shape and size of the holders may be varied at will to suit different-sized packages or different numbers of them. In the case shown the lower portion is reserved for bulk seed. 75

Having now fully described my invention, what I claim, and desire to secure by Letters Patent of the United States, is—

1. A seed-packet holder, consisting of a box having a bottom, sides folded upward 80 from said bottom, a back folded upward from said bottom and sides folded forward from said back, the two sets of sides being united into one by a cross-strip bent to form a shoulder at each end to hold the sides apart and 85 having its ends passed through said sides and then bent against said shoulders to clamp the sides together, substantially as shown and described.

2. In a seed-packet case, the combination, 90 with an open-front box having a plurality of shelves, of removable compartments for said shelves, each being open at the top and front, and having a bottom, a back, and parallel sides, a strip uniting said sides across the 95 front at the bottom, and a strip across the front intermediate the bottom and top, substantially as shown and described.

3. In a seed-packet case, the combination with an open-front box, having a plurality of shelves, of removable compartments each being open at the top and front, and having a 5 retaining-strip across said front near the bottom and a second retaining-strip across said front intermediate the bottom and top of same, substantially as shown and described.

In testimony whereof I have signed my name to this specification in the presence of two subscribing witnesses.

JOE L. ULLATHORNE.
